United States Patent Office

Des. 224,110

Patented July 4, 1972

224,110

DATA DISPLAY CONSOLE

Richard F. Heimann, 179 Concord Road,
Sudbury, Mass. 01776

Continuation-in-part of design application Ser. No. 21,170,
Jan. 30, 1970. This application Dec. 2, 1970, Ser.
No. 26,276

Term of patent 14 years

Int. Cl. D14—02

U.S. Cl. D26—5

FIG. 1

FIG. 3

FIG. 2

FIG. 1 is a perspective view showing the front, right side, and top of a data display console embodying the invention.

FIG. 2 is a perspective view of the rear, left side and top of the invention illustrated in FIG. 1; and

FIG. 3 is a top plan view.

This application is a continuation-in-part of my design application Ser. No. D. 21,170, filed Jan. 30, 1970, now abandoned.

I claim:

The ornamental design for a data display console, as shown and described.
